UNITED STATES PATENT OFFICE.

JOHN BOYLAN, OF GREAT NECK, NEW YORK.

DESIGN FOR A FINGER-RING.

52,779.

Specification for Design.

Patented Dec. 24, 1918.

Application filed September 7, 1918. Serial No. 253,080. Term of patent 3½ years.

To all whom it may concern:

Be it known that I, JOHN BOYLAN, a citizen of the United States of America, residing at Great Neck, in the county of Nassau and State of New York, have invented a new, original, and ornamental Design for a Finger-Ring, of which the following is a specification, reference being had to the accompanying drawing, forming part thereof.

In the drawings,—

Figure 1 is a plan view of a finger ring, showing my new design;

Fig. 2 is a side elevation, and

Fig. 3 is a side elevation looking in the opposite direction.

I claim:

The ornamental design for a finger ring, as shown.

In witness whereof I have hereunto signed my name.

JOHN BOYLAN.
